UNITED STATES PATENT OFFICE

THEODOR HITZLER, OF LEONBERG, GERMANY

INSOLE

Application filed December 10, 1930, Serial No. 501,403, and in Germany December 10, 1929.

The present invention relates to an insole constructed as an air cushion to facilitate walking and prevent premature fatigue. Furthermore, the insole has a general beneficial effect upon the health of the wearer by absorbing the shocks due to walking on hard ground, which are detrimental to certain organs of the human body, such as the kidneys.

10 The essential feature of the invention is that the top and bottom portions of the insole are connected over their entire surface by means of intermediate pieces or webs which are of the usual hollow type. This connection of the two insole portions over their entire area insures convenient walking even when continued for a long period of time, as the entire area is divided into small curved cushion units forming together a plane surface 15 which remains so during walking and also, owing to the presence of the webs which prevent bulging by the action of air pressed from one point to another. The distribution of the webs over the entire area of the insole 20 affords the added advantage of inflating the insole thoroughly without causing it to bulge.

In the known types of insoles provided with air cushions the insole is subdivided only into a number of large spaces or its two walls 25 are connected by lattice-like intermediate pieces. In the first case, the air blown in even at a comparatively low pressure will cause the insole to bulge to such an extent that walking becomes uncomfortable; and in the second case, inflation of the numerous tiny lattice cells is impossible so that the insole is filled only insufficiently with air of normal pressure.

One embodiment of the invention is illustrated in the accompanying drawing, in which Figure 1 is a diagrammatic longitudinal section showing the invention; Fig. 2, a vertical longitudinal section of an insole ready for use; Fig. 3, a top view thereof; and Fig. 4, a 45 vertical section on an enlarged scale of a portion of the insole prior to inflation.

Referring to the drawing, the insole in the modification shown is provided at the ball and heel portions with the air cushions *a* 50 which may, however, differ from the example

disclosed both as to number and arrangement.

The upper wall *b* and the lower wall *c* of the air cushions preferably made from rubber are interconnected by means of the webs *d* which may be hollow as shown at *e* if desired 55 in a preferably inextensible manner so that the subdivision of the cushion permits only the formation of very slight elevations between the various points of connection.

I claim:—

60 A removable insole adapted to be placed in a shoe comprising a top wall, a bottom wall, and a plurality of hollow webs interconnecting the two walls together thereby forming air cushions between the walls and the insole 65 permitting the passage of air therethrough by means of the webs.

In testimony whereof I affix my signature.
THEODOR HITZLER.
